UNITED STATES PATENT OFFICE.

CLAUDE L. FRIEL, OF CHICAGO, ILLINOIS, ASSIGNOR OF ONE-THIRD TO LEGRAND FRIEL, OF LOS ANGELES, CALIFORNIA, AND ONE-THIRD TO GRANT FRIEL, OF CHICAGO, ILLINOIS.

PRINTING-PRESS.

1,370,421.

Specification of Letters Patent.

Patented Mar. 1, 1921.

Application filed May 27, 1920. Serial No. 384,536.

To all whom it may concern:

Be it known that I, CLAUDE L. FRIEL, a citizen of the United States, residing at Chicago, in the county of Cook and State of Illinois, have invented certain new and useful Improvements in Printing-Presses, of which the following is a full, clear, and exact description.

My invention relates to job printing presses and particularly to the type known as Gordon presses.

Heretofore when printing the business headings or names of the drawers of checks on pages of check books containing more than one check, it has been customary to immovably adjust the chase in one position for the lower checks, and after printing all of the lower checks readjust the type in the chase for the checks next the lowest and to then print them, and then adjust the type for the checks above the last mentioned checks and so on. The feeding of each sheet of checks in this manner requires great activity on the part of the operator, and involves a great loss of time both in printing them and changing the chase and the "make-up" of the same.

The object of my invention is to avoid the necessity for such expert labor and the loss of time involved in the changing of the chase and to do this by comparatively inexpensive mechanism that intermittently shifts the chase from one predetermined position to another on the face of the bed, and which can be readily applied to either an old or new press. This I accomplish by the means hereinafter fully described and as illustrated in the drawings, in which:

Figure 1 is a side elevation of a Gordon job press, showing my improvements applied thereto.

Fig. 2 is a transverse section taken on dotted line 2, 2, Fig. 1.

Fig. 3 is a horizontal section taken on dotted line 3, 3, Fig. 1.

Fig. 4 is a horizontal section of a fragment of the bed of the press taken on dotted line 4, 4, Fig. 2.

Fig. 5 is a vertical section taken on dotted line 5, 5, Fig. 2.

Fig. 6 is a view similar to Fig. 5 showing the changed positions of the parts thereof.

Fig. 7 is a side view of a fragment of

the cam used in conjunction with my improvements.

Fig. 8 is a transverse section of the same taken on dotted line 8, 8, Fig. 7.

Fig. 9 is a perspective view of a broken away portion of the chase and carrier therefor, removed from the press.

The job printing press to which my improvements have been applied comprises a supporting frame, between the stationary side-frames A, A, of which the tiltable platen B is mounted. The platen is actuated by mechanism, which is suggested in Fig. 1 of the drawings, but which, in view of the fact that it does not constitute any part of my invention and is well known and in extensive use, it is not necessary to describe in detail, further than to say that the drive-shaft C is journaled in said side-frame A, A, and has a flywheel D on one end and a pulley E on the other.

The oscillating frame that supports the bed of the press consists of two corresponding legs 11, 11, the lower ends of which are mounted on a transverse horizontal rock-shaft 12 journaled in suitable bearings in the said side-frames A, near the rear edges 80 thereof just above the floor. The upper portions of these legs are shaped so that they are nearer together than their lower portions and are connected by the vertical transversely disposed bed 13 the front of 85 which is perfectly flat and provides a vertical transverse surface that extends from one side-frame to the other for the chase (hereinafter more fully described) to rest against.

The sides of this bed have vertical guide-cleats 14, 14, screwed or otherwise secured to the same, and the vertical edges of the rear sides of these cleats are rabbeted to form runways for the end edges of the chase 95 carrier. This carrier consists of end members 15, that are Z-shaped in horizontal section to provide lips 20 and the rear sides of these end members are connected by a back-plate 16, and their lower ends are connected 100 by a horizontal strip which may be in one piece with the back-plate 16 if desired and which forms a supporting ledge 17, for the chase 18.

Chase 18 is constructed in its essentials 105 like any of the chases now in extensive use

except that, as shown in the drawings, it is less in height and the vertical edges of the outer surfaces of its ends are rabbeted to provide runners 19, that are adapted to 5 slide back of and be retained in place by the overlapping lips 20 of the ends of the carrier.

The object of my invention is to make the first of a cycle of, say, three impressions on 10 sheets each having three checks previously printed thereon, or on sheets having several printed forms of other matter, which has been fed to the platen B, when the carrier and chase are in the position shown in 15 full lines in Fig. 5 of the drawings; to make the second impression when they are in the position shown in dotted lines in said figure; to make the third impression when they are in the position shown in Fig. 6 of 20 the drawings, and then to commence the next cycle of impressions by returning the chase to the position shown in said Fig. 5.

In order to enable these impressions to be made in succession, it is obvious that the 25 chase must be given an intermittent movement from one position to the next position in which it must be in, in order to make the successive impressions. In order to accomplish this I secure rods 21 to each end of 30 the carrier which extends downward a distance slightly exceeding the distance which the carrier and chase travel to make their plurality of impressions, and pivotally secure the lower ends of these rods to the forward end of longitudinal plungers that slide in and out of the bores of the tubular front ends of levers 23. These levers extend from a point at the rear of the lower end of rods 21 to a point, preferably, at the rear of the 35 inking-plate actuating mechanism G of the press, and their rear ends are fulcrumed on a rock-shaft 24. The ends of said rock-shaft are journaled in the rear ends of brackets 25 that are secured to and project to 40 the rear from legs 11 of the oscillating frame. Levers 23 are moved up and down through the medium of a friction roller 50 and cam 26. The friction roller is journaled in the bifurcations 27 projecting forward 45 from the vertex of a horizontally disposed V-shaped frame 28, the ends of the arms of which extend rearwardly and are made integral with the said levers near their fulcrums.

50 Cam 26 is mounted on a transverse shaft 29, midway between the brackets 25, 25, in which it is journaled, and one end of this shaft extends through its bearings and is provided with a sprocket-wheel 30. This 55 sprocket-wheel 30 is driven through the medium of a chain 31 by a small sprocket-wheel 32 on a horizontal shaft 33, which is journaled in a standard 34 and in bearings in the adjacent side-frame A in axial 60 alignment with the rock-shaft, 12, on which

the legs 11 of the oscillating frame are mounted.

The shaft 33 extends beyond the sprocket 32 and has another sprocket 35 securely mounted thereon, and this latter sprocket 70 and said shaft are driven through the medium of a chain 36 and a sprocket (not shown) on the drive-shaft C.

The means just described for imparting the motion of the drive-shaft C to the cam-shaft 29 revolves said cam-shaft once while the platen and bed engage three times, and thus brings the cam into three different positions at 120 degrees apart synchronously with the first, second and third positions, 75 respectively, occupied by the carrier and chase in making its three impressions. This cam is so shaped that when the carrier and chase are in their lowest positions to make the first of the cycle of impressions, the 80 friction roller 25 will engage a segment 26^a of its periphery approximately one sixth of a circle which is struck from the minor radius of this cam and while the friction wheel engages this segment 26^a, the carrier 85 and chase will be stationary. As the friction roller passes out of engagement with the segment 26^a it is raised and simultaneously raises levers 23 and the carrier and the chase until it reaches the intermediate 90 segment 26^b of the cam, which latter represents the intermediate radius of the cam and holds the chase and carrier stationary in their second position while the second 95 impression is being made. The friction 100 roller then passes out of engagement with segment 26^b and is raised so as to raise the levers and the carrier and chase to the third or highest position on the bed and comes into engagement with the segment 26^c 105 which latter is struck from the major radius of the cam. While the friction roller is traveling over segment 26^c the carrier and chase are held stationary while the press is making the third impression of the cycle 110 of impressions. After the friction roller leaves segment 26^c the shape of the perimeter of the cam is such that said roller, levers, carrier and chase drop down to their lowest 115 position at which point the roller engages segment 26^a again.

In order to enable the length of each intermittent movement of the carrier and chase to be adjusted so as to make each impression register on each check or form in 120 the exact position desired on the sheet that is being printed upon, I have made the intermediate segment and major segment adjustable to and from the axis of the cam-shaft. This I accomplish by means of channeled shoes, 37 and 38, that are, respectively, seated in proper positions over the segments 26^b and 26^c. These shoes have screws 39 and 40, respectively, projecting radially 125 inward into smooth bores 44 in the cam 130

which latter has lateral openings 41 that are intersected by said screws. Nuts 42 and 43 are mounted upon the threaded portions of said screws, passing through these openings 5 and by manipulating said nuts, the shoes may be adjusted so as to obtain just the length of the intermittent movement of the chase and carrier to make the impression printed by said chase to register exactly at 10 the point desired on the check or other form printed upon.

What I claim as new is:

1. In a printing press, a platen, a bed, a chase mounted on said bed and a form 15 locked therein, which chase is intermittently movable thereon to and from one position to another and adapted to print from the same type while at rest in each of said positions when said platen and bed are in engagement.

2. In a printing press, a platen, a bed, a chase mounted on said bed and a form 20 locked therein, which chase is intermittently movable from a lower to superposed position thereon and adapted to print from the same type while at rest in each of said positions when said platen and bed are in engagement.

3. In a job printing press, a tiltable platen, an oscillating bed engaged thereby, a 30 chase mounted on said bed and form locked therein, which chase is intermittently movable thereon to and from one position to another and adapted to print from the same type while at rest in each of said positions when said platen and bed are in engagement.

4. In a job printing press, a tiltable platen, an oscillating bed engaged thereby, a chase, and a form locked therein, which are 40 intermittently movable to several positions arranged one above the other and adapted to print in repetition a cycle of impressions from the same type while at rest in each of said positions and in succession from the lowermost to the uppermost.

5. In a printing press a platen, a bed 45 adapted to be engaged thereby, a chase, a form locked therein, and a carrier therefor which is intermittently movable thereon to and from one position to another on said bed, and which retains said chase in each of said positions while the latter prints from the same type during each period of rest.

6. In a printing press a platen, a bed 55 adapted to be engaged thereby, a chase mounted on said bed, a form locked therein, said chase being intermittently movable on said bed to and from one position to another and adapted to print from the same type while at rest in each of said positions 60 when said platen and bed are in engagement, and means for adjusting the distance between said positions.

7. In a printing press, a platen, a bed 65 engaged thereby, parallel cleats at opposite sides thereof, a reciprocal chase mounted on

said bed, a form locked therein, which chase has an intermittent movement thereon in one direction and guided by said cleats from one position to another and adapted to print from the same type while at rest in each of 70 said positions when said platen and bed are in engagement.

8. In a printing press, a platen, a bed engaged thereby, parallel cleats at opposite sides thereof, a reciprocal chase mounted on 75 said bed, a form locked therein, which chase has an intermittent movement thereon in one direction and guided by said cleats from one position to another and adapted to print from the same type while at rest in each of 80 said positions when said platen and bed are in engagement, and means for adjusting the distance between said positions.

9. In a printing press, a platen, a bed, a chase mounted on said bed which is intermittently 85 movable thereon to and from one position to another and adapted to print while at rest in each of said positions when said platen and bed are in engagement, and a cam for actuating said chase, and means for transmitting movement from said cam to said chase.

10. In a printing press, a platen, a bed engaged thereby having vertically disposed parallel cleats secured to opposite sides of 95 the same, a chase, a form locked therein, a carrier in which said chase is removably seated whose ends have a sliding engagement with said cleats and has a reciprocal movement that is intermittent from a lower 100 to a superposed position in each of which positions an impression is made by the same type while the chase is at rest, and means for imparting said movement to said carrier.

11. In a printing press, a platen, a bed 105 engaged thereby having a platen, parallel vertical cleats secured to opposite sides of said bed, a chase, a carrier therefor the ends of which have a sliding engagement with said cleats, rods extending down from 110 said carrier, levers which are fulcrumed at their rear ends, reciprocal extensions in the forward ends of said levers that are pivotally connected to the lower ends of said rods, and means that impart to the levers 115 and to said rods and carrier a reciprocal movement which is intermittent in one direction whereby said chase is adapted to print while at rest when said platen and bed are in engagement.

12. In a printing press, a platen, a bed engaged thereby having a platen, parallel vertical cleats secured to opposite sides of said bed, a chase, a carrier therefor the ends of which have a sliding engagement with said 125 cleats, rods extending down from said carrier, levers which are fulcrumed at their rear ends, reciprocal extensions in the forward ends of said levers that are pivotally connected to the lower ends of said rods, and 130

means including a cam that impart to the levers and to said rods and carrier a reciprocal movement which is intermittent in one direction whereby said chase is adapted to print while at rest when said platen and bed are in engagement.

13. In a printing press, a platen, a bed engaged thereby having a platen, parallel vertical cleats secured to opposite sides of said bed, a chase, a carrier therefor the ends of which have a sliding engagement with said cleats, rods extending down from said carrier, levers which are fulcrumed at their rear ends, reciprocal extensions in the forward ends of said levers that are pivotally connected to the lower ends of said rods, and means including a cam, and an anti-friction roller engaged thereby, and a cross-frame connecting said levers in the structure of which said roller is journaled.

14. In a printing press a platen, a bed adapted to be engaged thereby, a chase mounted on said bed, which is intermittently movable thereon to and from one position to another and adapted to print while at rest in each of said positions when said platen and bed are in engagement, a cam, means through the medium of which said cam actuates said chase, and adjustable segments mounted on the perimeter of said cam for adjusting the distance between the positions assumed by said chase.

15. In a printing press, a rocking platen, a stationary frame in which the same is mounted, a drive shaft journaled in said frame, a bed having integral legs that are pivotally connected to said frame, a chase which is intermittently movable on said bed to and from one position to another and which is adapted to print while at rest in

each of said positions when said platen and bed are in engagement, devices that actuate said chase and means driven by said drive shaft that oscillate said bed and impart motion to said devices.

45

16. In a printing press, a rocking platen, a stationary frame in which the same is mounted, a drive shaft journaled in said frame, a bed having integral legs that are pivotally connected to said frame, a chase which is intermittently movable on said bed to and from one position to another and which is adapted to print while at rest in each of said positions when said platen and bed are in engagement, a cam that actuates said chase and means driven by said drive shaft that oscillate said bed and impart motion to said cam.

50

17. In a printing press, a rocking platen, a stationary frame in which the same is mounted, a drive shaft journaled in said frame, a bed having integral legs that are pivotally connected to said frame, a chase which is intermittently movable on said bed to and from one position to another and which is adapted to print while at rest in each of said positions when said platen and bed are in engagement, a cam that actuates said chase, a shaft therefor, means driven by said drive-shaft that oscillate said bed, and sprocket wheels and chains that impart motion from said drive-shaft to said cam-shaft.

55

60 In witness whereof, I have hereunto set my hand.

CLAUDE L. FRIEL.
